DESIGN FOR A COMB

Herman J. Schelhammer, Whitestone, N. Y., assignor to American Hard Rubber Company, New York, N. Y., a corporation of New York

Application November 16, 1937, Serial No. 72,926

Term of patent 14 years

To all whom it may concern:

Be it known that I, Herman J. Schelhammer, a citizen of the United States and a resident of Whitestone, in the county of Queens, in the State of New York, have invented a new, original, and ornamental Design for a Comb, of which the following is a specification, reference being had to the accompanying drawing, forming a part thereof and in which:—

Fig. 1 is a side elevation of a comb embodying my new design, the reverse side of the comb being substantially of the same appearance as

the side shown; and Fig. 2 is a top plan of the comb shown in Fig. 1.

The characteristic feature of the design resides in a comb having alternate groups of relatively coarse and fine teeth with the teeth in the fine groups exceeding in number the teeth in the coarse groups.

I claim:—

The ornamental design for a comb as shown and described.

HERMAN J. SCHELHAMMER.
